United States Patent Office.

D. T. WARD, OF CARDINGTON, OHIO.

Letters Patent No. 71,931, dated December 10, 1867.

IMPROVED WASHING-MACHINE.

The Schedule referred to in these Letters Patent and making part of the same.

TO ALL WHOM IT MAY CONCERN:

Be it known that I, D. T. WARD, of Cardington, in the county of Morrow, and State of Ohio, have invented certain new and useful Improvements in Washing-Machines; and I do hereby declare that the following is a full and exact description thereof, reference being had to the accompanying drawings, making part of this specification, in which—

Figure 1 is a longitudinal vertical section of my improved machine.

Figure 2, a transverse section thereof.

Like letters designate corresponding parts in both figures.

My invention consists in the combination of a horizontal wash-board with a segmental one, provided with a lever, by which the two are operated, and the clothes washed by being compressed between the boards, and in the use of a spring in connection therewith, all as hereinafter fully set forth.

As represented in the drawings, A is a rectangular tub, with the standards B B at the sides opposite each other, in which is mounted a horizontal axis, *c*, that connects them and forms the fulcrum for the two levers D D. The lower ends of these levers are enlarged in the form of a segment, between which are secured the strips forming the convex wash board E. F is a horizontal wash-board, with a raised ledge, *g*, on each side, which serves to retain the water and clothes on the board while the latter are being subjected to the action of the convex surface of the board E. This board is coupled to the levers D by means of arms H H hinged at one end to the top of the ledges *g*, and at the other pivoted to the levers, or, preferably, secured by a notch fitting over a screw, *i*, as represented, so as to be readily disconnected when required. Surrounded and fastened to the axis *c* is a spiral spring, *j*, the outer end engaging under a cross-rod, *k*, which extends across the machine, as shown. The axis *c* has its bearings in slots *l*, made in the top of the standards B. The wash-board F rests on two longitudinal pieces, M M, at the bottom of the tub on each side, which are provided with a vertical mortise, *n*, at their centre, in which are arranged two friction-rollers, *o o*, on which the board F rolls as it is operated back and forth by the levers D and connecting-arms H, as will presently be described. The end of board F has secured to it a gate, *p*, which projects downward, closing the space between the sills M. It may be hinged to the wash-board as shown, if preferred, so as to turn up when its use is not required. N is a brace or stay, connecting the levers D, as represented. The end of the wash-boards may be made plain, as shown; corrugated, perforated, constructed of yielding slats, or covered with canvas, rubber, &c., or of any other suitable construction.

The operation of my improvements is as follows: The water and garments to be washed being put in the tub, the levers D are turned back, as shown in red lines, elevating the board E, enabling the clothes to be readily arranged on the horizontal one, F, when the levers are operated by the cross round *g*, at the end of the levers, which causes the segmental board E to compress the clothes upon the horizontal board, while it at the same time moves the latter longitudinally (shown in red lines) by means of the connecting-arms H. This downward movement of the levers (as indicated by arrows) compresses the spring *j*, the end of which being engaged under the rod *k*, operates to press the board E with greater or less force, according to the stiffness of the spring on the clothes beneath, the slots in the standards allowing the necessary adjustment of the axis *c*, while the elasticity of the spring allows the board to yield to the varying thickness of the garments operated on. The gate *p*, attached to end of board F, as before described, operates, as the board reciprocates, to alternately dam up the water at either end, so as to overflow the clothes and horizontal board at the same time it and the end of the board squeeze the garments between them and the end of the tub. By this it is manifest that my machine has a twofold action in washing, viz., compressing the clothes between the two wash-boards, and also in the manner just described, which combined action accomplishes the desired result of washing and rinsing the clothes in the most rapid and thorough manner. The spring *j* not only operates as before specified, but also assists in raising the depressed levers to their normal position, which is the more laborious. The cross-rod *k* is designed to be made of such size that it will yield and operate as a spring to a certain extent. If either or both of the beds of the wash-boards are made elastic, the use of the spring *j* may be dispensed with by mounting the axis *c* in rigid boxes, although I prefer to employ them in both cases.

What I claim as my invention, and desire to secure by Letters Patent, is—

1. The segmental or convex wash-board E, actuated by levers D, in combination with the reciprocating wash-board F and connecting-arms H, substantially in the manner and for the purpose set forth.
2. I also claim, in combination therewith, the spring j, rod k, and slots l, arranged and operating substantially as described.
3. I also claim the gate p, in combination with the horizontal reciprocating wash-board F, and tub A, arranged and operating substantially as and for the purpose set forth

In witness whereof, I have hereunto signed my name in the presence of two subscribing witnesses.

D. T. WARD.
